UNITED STATES PATENT OFFICE

LEO T. TAFFE, OF DETROIT, MICHIGAN, ASSIGNOR TO IDEAL ENGINEERING SPECIALTY COMPANY, OF DETROIT, MICHIGAN, A CORPORATION OF MICHIGAN

DOORCHECK HINGE

Application filed November 18, 1929. Serial No. 407,965.

This invention relates to door checks of the type adapted to be used in connection with the doors of automobiles and similar vehicles, and has for its object the provision of a simple, efficient and improved check of this character which is compactly associated with and forms a part of the hinge unit assembly.

The invention is fully described in the following specification, and while in its broader aspect it is capable of embodiment in numerous forms, a preferred embodiment thereof is illustrated in the accompanying drawings, in which,

Figure 1 is a perspective view of a hinge embodying the invention in mounted relation to a door and frame-post which are fragmentarily shown in open relation, and Fig. 2 is an enlarged vertical fragmentary section taken on the line 2—2 in Fig. 1, with parts in full.

Referring to the drawings, 1 designates an automobile door and 2 the pillar or post of the associated body frame to which the door is hung by a set of hinges, the lower one 3 of which is shown.

This hinge is of the double leaf type commonly used for the hanging of automobile doors and each leaf is provided with a slot 4, which is disposed lengthwise of the leaf from near its inner end to a point adjacent to its outer end and in register with the other slot when the hinge is in closed position.

The check means embodying the invention comprises a pair of links 5 and 6 that are pivotally connected at their inner ends, a third link 7 that is pivotally connected, in the present instance, to the outer end of the link 6, and a cushion or shock absorbing spring 8 mounted on the link 7, the axes of the link pivots being parallel to the axis of the hinge pivot.

The link 5, in the present instance, has its outer end projected outwardly through the outer end portion of the slot 4 of the hinge leaf a, which is the one attached to the door, and is pivoted to the hinge leaf at the door side thereof, as to a block 9 secured thereto, so that the link may swing into and out of the slot.

The link 6 has the end thereof opposed to the link 5 projecting through the outer end

portion of the slot 4 in the hinge leaf b and pivotally attached to the link 7 normally at the post side of the leaf, the link being shown as of rod form and having at its inner end a right angled bend, which pivotally engages an eye in the link. The spring 8 encircles the link 7 with one end thrust against a block 10 attached to the leaf and with the outer end thrust thereof against a shoulder 11 on the link, which shoulder may be a nut threaded on the link to permit adjustment of the tension of the spring. A pull exerted on the link 6 through the link 5 causes a movement of the link 7 through a laterally enlarged portion 12 of the associated slot 4 to an extent permitted by the spring. The block 10 is also slotted to receive the end of the link 6 and to permit the projection therethrough of the link 7.

The links 5 and 6 are of thin form so that the vertical space occupied thereby is a comparatively small portion of the vertical depth of the hinge leaves. The slot 4 in which the links fold may, therefore, be narrow and not effect any serious weakening of the hinge.

The inner end of one of the links 5, 6, is provided with a stop lug 13, which engages the other link to prevent the links from completely straightening out when the hinge is opened, which would cause a locking of the hinge against closing until the links are again broken.

It is evident that the check means is disposed at practically the free ends of the hinge leaves and that the mortise 14 in which the link 7 and spring 8 are disposed is at the inner side of the post 2 and easy of access to adjust the nut for tensioning the spring or for the removal of parts for replacement or repair.

It is apparent that the opening movement of the door is limited by the check means and that any shock on said means, in stopping an opening movement of the door, is cushioned and absorbed by the spring 8. When the hinge leaves are in closed relation, they are closely folded together and the check links 5 and 6 are folded one over the other within the slots 4. It is preferable to have the outer end portions of the links 5 and 6 slightly

angled so that when the hinge is opened to its limit, said portions will project through and from the respective hinge leaves and at right angles thereto.

5 I wish it understood that my invention is not limited to any specific construction, arrangement or form of the parts, as it is capable of numerous modifications and changes without departing from the spirit of the claims.

10 Having thus described my invention, what I claim as new and desire to secure by Letters Patent is:

1. In combination, a hinge having leaves adapted to close in substantially close parallel relation and each having a longitudinally disposed slot therein extending to near the outer ends of the leaves, a pair of check links foldably hinged together and one having its outer end projecting through the outer end portion 20 of the slot of one leaf and pivotally attached to such leaf and the other link having its outer end projected through the outer end portion of the slot of the other leaf, a third link pivotally attached to the free end of said second link and projecting away from the outer side of the associated hinge leaf, and a spring mounted on said third link and coacting with it and the adjacent hinge leaf to cushion a pull exerted by the other links, said second 30 and third links being adapted to lie in said slots when the hinge is in closed position.

2. In combination, a hinge having leaves adapted to close in substantially close parallel relation and each having a longitudinally disposed slot therein, a pair of check links pivoted together at their inner ends and each having its outer end projected through the outer end portion of the slot of a respective leaf of the hinge and one being pivoted at its outer end to the associated hinge leaf, a third link pivoted to the free end of said outer link and having a stop shoulder thereon, a compression spring mounted on said third link with one end thrust against said shoulder and 45 its other end thrust against the outer side of the associated hinge leaf to act through the links to yieldingly check an opening of the hinge when it has been opened a predetermined extent, the several connecting pivots 50 of said links being parallel to the connecting pivot of the hinge leaves and the two first links being folded one over the other within the leaf slots when the hinge is closed.

3. In combination, a hinge having leaves adapted to close in substantially close parallel relation and each having a longitudinally disposed slot therein, a pair of check links pivoted together at their inner ends and each having its outer end projected through the outer end portion of the slot of a respective leaf of the hinge and one being pivoted at its outer end to the associated hinge leaf, a third link pivoted to the free end of said other link and having a stop shoulder thereon, a compression spring mounted on said third link

with one end thrust against said shoulder and its other end thrust against the outer side of the associated hinge leaf to act through the links to yieldingly check an opening of the hinge when it has been opened a predetermined extent, the several connecting pivots of said links being parallel to the connecting pivot of the hinge leaves and the two first links being folded one over the other within the leaf slots when the hinge is closed, said first mentioned links having provision for stopping their opening movements before they have assumed a completely straightened out position.

4. The combination with a hinge having leaves adapted to close in substantially close parallel relation and each having a slot therein, of a yielding check for the hinge comprising a pair of links pivotally connected together with the outer end of one link pivoted to one leaf of the hinge near its outer end, and means yieldingly connecting the outer end of the other link to the other leaf near its outer end, said links being adapted to fold together and to lie in said slot when the hinge is in closed position.

In testimony whereof I have hereunto signed my name to this specification.

LEO T. TAFFE.
